UNITED STATES PATENT OFFICE

2.151.986

DROSS SIFTER

Leonard G. Olander, Minneapolis, Minn., assignor to The Monomet Company, Incorporated, Minneapolis, Minn., a corporation of Minnesota.

Application June 22, 1936, Serial No. 86,614

3. Claims. (Cl. 209—324)

This invention relates to a sifting device and particularly to such a device for sifting dross which is skimmed from the top of molten metal, such as type metal.

5 In printing shops, particularly those of larger size, there is a very considerable accumulation of dross which is skimmed from the top of the molten type metal in the various melting pots for the type metal. It is a common practice to
10 preserve this dross and place it in a so-called dross drum which is generally in the form of a comparatively large cylinder. One very common form of dross drum has a cylindrical open top with a flange projecting inwardly adjacent the
15 top, which flange is provided for supporting a cover placed on the drum when it is to be closed for shipment.

When the dross is skimmed there is usually some type metal taken with it. The dross proper is in the form of a fine powder or will take this form by agitation. The dross can be sifted from the metal with a proper apparatus.

It is an object of this invention to provide a simple and efficient sifting device which may be used directly with the dross drum so that the sifted dross will pass into the drum and the type metal will be recovered.

It is a further object of the invention to provide a sifting device comprising a member having a supporting means resting on top of the dross drum and having a portion extending down into the dross drum, said member also having means at its inner side for supporting a sifter which is oscillatable thereon, together with a cover for said member.

It is another object of the invention to provide such a device as set forth in the preceding paragraph together with an agitator movable over the bottom of said sifter, which agitator is operable from the upper side of said cover.

10 It is still another object of the invention to provide a sifting device to be used with a dross drum comprising a member supported on and extending a short distance into the drum and 45 having an upstanding wall, a sifter having a foraminous bottom supported within said member and having a handle projecting through the wall of said member by which it can be oscillated, together with a cover for said member and an agitator 50 movable over said bottom and operated by means at the outer side of said cover.

These and other objects and advantages of the invention will be fully set forth in the following description made in connection with the accompanying drawing, in which like reference char-

acters refer to similar parts throughout the several views and in which:

Fig. 1 is a view of the device of this invention in central vertical section, the lower portion of a gross dium being shown in side elevation; and

Fig. 2 is a top plan view of the device shown in Fig. 1, certain parts being broken away.

Referring to the drawing, a container 10, commonly known as a dross drum is shown, the same being cylindrical having an open upper end provided with beads 10a at its top and bottom. Said container has a pair of annular ribs 10b extending thereabout to protect it in handling and shipment and the same also has projecting inwardly from its inner side and adjacent its top a flange 10c. 15

13a at the bottom thereof. A screen 13c of coarse mesh and which is preferably made of steel is supported on top of rim 13b and a fine mesh screen 13d overlies and is supported on screen 13c. While screen 13d may be made of various metals, in practice it has been found satisfactory to make this screen of brass. Screens 13c and 13d extend substantially to the wall 13a and a rim 13e of small thickness extends about the edge of said screens adjacent wall 13a. A multiplicity of headed and nutted bolts 13f extend through rims 13b and 13e and through screens 13c and 13d, thus securing said parts firmly together. A handle 13g is secured to the outer side of wall 13a in any suitable manner and projects radially from wall 13a through a slot 11e in wall 11c. Said slot 11e is disposed just above the flange 11b and extends for some distance about wall 11c, the same having a vertical portion at its center extending to the top of wall 11c. A cover 14 is 55

provided having a cylindrical portion 14a with a bead 14b at its bottom, said cover having a portion 14c extending upward slightly and having a flat top 14d. Said cover is preferably formed of sheet metal and has reinforcing bars 15 at its under side intersecting at the center thereof and secured thereto by headed and nutted bolts 16. A bearing 17 extends downwardly centrally from bars 15 and a shaft 18 is journaled in said bearing, the same passing through cover 14 and having a collar 18a thereon resting on top of cover 14. Above collar 18a shaft 18 is bent at a right angle to form a crank, the vertically extending end of which is provided with a handle 19. Shaft 18 has secured to its lower end an agitator 20 having a central hub 20a to which shaft 18 is secured and having a plurality of radially and angularly extending arms 20b, the same being shown as three in number. The lower edges of arms 20b are disposed in close proximity to the top of screen 13d. Cover 14 fits tightly over the top of member 11.

In operation the dross with the particles of type metal therein is placed in the screen 13, 25 cover 14 with the crank and agitator 20 being removed. It is best not to fill the sifter over half full. The cover is then replaced and the crank is given five or six revolutions by handle 19, thus operating the agitator 20. The agitator 30 tends to draw the cover 14 down tightly on member 11. The material in the sifter is thus thoroughly agitated and the dross powder passes through the screens into container 10. The sifter can be oscillated or shaken several times by 35 means of handle 13g. This brings the material toward the center of the screen. Cover 14 can then again be removed and the sifter 13 lifted from member 11 and the type metal which is now left on the screens can be discharged into the place desired. In practice it takes only about ten 40 minutes to run 100 pounds of dross material through the sifter. The metal is thus quickly separated from the dross and a saving of from 150 to 250 pounds of type metal is made on each 45 500 pound drum full of dross.

From the above description it will be seen that 45 applicant has provided a very simple and efficient device for separating the dross powder from the type metal. The device is easily operated and the same effects a great saving in type metal. The device can be operated without any dust or 50 dirt escaping into the room where it is located. The device is of rugged construction and very durable. The same has been amply demonstrated in actual practice, found to be very successful and efficient and is being commercially 55 made.

It will, of course, be understood that various 60 changes may be made in the form, details, arrangement and proportions of the parts, without departing from the scope of applicant's invention, which generally stated, consists in a device capable of carrying out the objects above set forth in the parts and combinations of parts 65 disclosed and defined in the appended claims.

What is claimed is:

1. A sifting device for a dross drum, which drum has a cylindrical top and an inwardly projecting flange a short distance below said top having in combination, a member having a cylindrical portion constructed and arranged to fit into said drum within said flange and having an outwardly extending flange thereabout adapted to rest on top of said drum, said member having a second cylindrical portion extending upwardly from said flange and having a second flange extending inwardly therefrom, a sifter having a flat screen, a cylindrical wall surrounding the same disposed within said second cylindrical portion and terminating short of the top thereof and having a flange resting on said second flange for oscillation thereon, a handle secured to said sifter for oscillating the same and extending outwardly through a slot in said second cylindrical portion, an imperforate cover having a cylindrical wall fitting about said second cylindrical portion, resting thereon and readily removable therefrom, said cover having a bearing centrally disposed in its top, a shaft extending through said bearing, a rotatable stirrer having a plurality of circumferentially spaced arms disposed within said sifter and above said screen thereof and carried on the lower end of said shaft and a crank handle secured to said shaft above said cover. 20

2. The structure set forth in claim 1 and means secured in said first mentioned cylindrical portion projecting outwardly therefrom below said flange of said drum to prevent vertical movement of said member relative to said drum. 30

3. A sifting device for a dross drum, which drum has an open cylindrical top having in combination, a cylindrical member having means extending outwardly therefrom intermediate its ends for engaging the top of said drum and supporting said member, the portion below said means extending into said drum, said member having means extending inwardly therefrom, a sifter comprising a flat screen and a cylindrical wall extending thereabout, said wall being disposed within said member and having a flange resting on said last mentioned means for oscillation thereon, said member having a slot extending therethrough extending circumferentially thereof, a handle secured to said sifter and extending outwardly therefrom through said slot for oscillating said sifter, an imperforate cover having a cylindrical portion fitting over and supported on the top of said member, a bearing carried by said cover, a shaft journaled in said bearing, a stirrer secured to the lower end of said shaft and having a plurality of arms extending outwardly therefrom in circumferentially spaced relation substantially to the edge of said screen and a handle secured to said shaft above said cover for rotating said shaft and stirrer whereby material in said sifter will be moved over substantially the whole area of said screen and may thus be efficiently sifted by said screen when oscillated by said first mentioned handle. 40 50 55 60 65
